Application September 18, 1952, Serial No. 310,269

4 Claims. (Cl. 155—194)

My invention relates to furniture and includes among its objects and advantages an increase in lightness and strength in steel members for furniture.

In the accompanying drawing:

Figure 1 is a perspective view of a folding chair;

Figure 2 is a fragmentary side view of one of the long leg members;

Figure 3 is a view, as in section on line 3—3 of Figure 2, showing the reinforcing insert in end view;

Figure 4 is a transverse section of a modified construction; and

Figure 5 is a detail on line 5—5 of Figure 2.

In the embodiment of the invention selected for illustration, the invention is incorporated in a conventional folding chair. This comprises long leg members 10 and 12, extending up to form the side members of the back, above the seat 14. The upper ends of the leg members are united by a curved bight 16, and the panel 18 set into the bight completes the back structure. The rear legs 20 and 22 are pivoted at their upper ends at 24 and 26 to the back leg members 10 and 12 above the level of the seat 14. The seat itself is pivoted to the leg members 10 and 12 at 28 and 30. The rear legs are cross-braced a short distance above the floor level by a cross-piece 32, and the front legs are similarly braced by a cross-piece 34.

Each of the leg members is a tube formed from a flat piece of sheet metal by curving it into the shape indicated in Figures 3 and 4. In one common size, such a leg is one inch in its major cross-sectional dimension, and three-quarters of an inch in a direction at right angles thereto. It includes the narrow portion 36 of relatively large radius of curvature, the lobes 38 and 40, and the turned-in edges 42 and 44 in the center of the relatively flat portion opposite the portion 36; these edges are not welded or otherwise united with each other, except that adjacent cross-brace 34, and adjacent the pivot 46 for the seat 14, they are cut away to receive the parts 34 and 36, and all the parts are then welded or brazed where they pass through, as indicated in Figures 2 and 3, by the lump of weld metal at 48 around the pivot 46 and a lump 50 around the cross-brace 34. Both the cross-brace 34 and the pivot 46 go on through the back of the leg structure and are riveted over on the outside as indicated in Figures 3 and 4 by the head 52.

The point of maximum bending load in such a leg is adjacent the pivot 46, but users not infrequently engage the cross-brace 34 with their feet so that impact is likely to be received at that level. I have found that a great increase in strength and durability under load is obtainable by means of a C-shaped insert 54, which fits snugly inside each of the legs 10 and 12, and extends about three-quarters of an inch below the brace 34, and about an inch and one half above the pivot 46. Such a relatively open C-shaped tube can be fashioned from thin sheet metal in the same way that the leg itself is fashioned. If it is originally formed of a size so that it can slide into place inside the leg, under a thrust of a hundred pounds or so, the resulting assembly, as indicated in Figure 3, does not have an absolutely perfect and continuous contact between the sleeve 54 and the leg. In Figure 3 I have indicated three short portions at 56, 58, and 60, where the inner layer of metal does not remain in perfect contact with the leg, and a slight clearance remains.

Referring now to Figure 4, if the insert 54 is originally

2

fashioned so that its undistorted shape before insertion is as indicated by the dotted line position, from three to ten times as much axial thrust may be necessary to make the assembly, and the corners of the metal at end inserted first should be twisted in about a sixteenth of an inch, with a pair of pliers or by impact, to help get started. By this method of assembly, it is possible to eliminate substantially all clearance between the leg and its reinforcing insert, and a minor fraction of additional mechanical strength under load is obtainable.

A satisfactory diameter for the pivot 46 is one-quarter inch. The pivot may be of uniform diameter throughout, as indicated in Figure 3. A satisfactory diameter for the cross-brace 34 is three-eighths inch. The additional material is needed because this member frequently carries a bending load. The extreme end of rod 34 is reduced in diameter, as indicated at 62 in Figure 5, so that the rivet head 52 grips both layers of sheet metal positively. The liner 54 is firmly anchored against longitudinal movement by both members 34 and 46, but the most complete clamping action is adjacent the member 34, remote from the point of maximum bending load at 46, so that the metal at 46 has a minimum of local residual stresses caused by the operation of assembly.

Others may readily adapt the invention for use under various conditions of service, by employing one or more of the novel features disclosed, or equivalents thereof. As at present advised, with respect to the apparent scope of my invention, I desire to claim the following subject matter.

I claim:

1. A structural member suitable for chair legs and similar uses, subject to compound loads, comprising, in combination: a single piece of sheet metal bent to form an outer tube, with the opposite longitudinal edges of the piece adjacent each other; said tube edges being turned inwardly to define stiffening flanges; and a one-piece sheet metal reinforcing liner also bent to form a tube; the liner edges being spaced apart to leave clearance for said inwardly turned tube flanges; said liner fitting snugly against the inner wall of said outer tube.

2. A member according to claim 1 in which the cross-section of said outer tube is an oblate circle having its maximum transverse dimension in a plane perpendicular to a median plane passing between said inwardly-turned outer tube edges.

3. A member according to claim 1 in which said liner in undistorted condition is too large to fit inside said outer tube and is slightly compressed within said outer tube, whereby both tubes are under a light permanent stress to hold them in firm contact.

4. A member according to claim 1 in combination with a transverse structural connecting rod intersecting the member and perpendicular thereto; said rod having its axis in a median plane of the member passing between said turned flanges; said rod penetrating the member and liner at a point diametrically opposite said turned flanges and anchoring said outer tube and liner against relative longitudinal movement.
